UNITED STATES PATENT OFFICE.

CHARLES C. MOORE, OF EL PASO, TEXAS, ASSIGNOR OF ONE-HALF TO ROBERT E. HARRIS, OF EL PASO COUNTY, TEXAS.

TOILET.

Application filed April 6, 1922. Serial No. 550,049.

To all whom it may concern:

Be it known that I, CHARLES C. MOORE, a citizen of the United States, residing at El Paso, in the county of El Paso and State 5 of Texas, have invented a new and useful Toilet, of which the following is a specification.

This invention aims to provide a simple means whereby persons in a car may be permitted to use a toilet whilst the car is passing through places wherein it is forbidden to permit defecatory matter to be deposited along the right of way, it being possible to dump the matter collected when an opportune occasion arises, an unauthorized dumping being practically impossible.

In the drawings:

Figure 1 is a side elevation, portions being broken away; Figure 2 is a sectional detail 20 showing the key; Figure 3 is an end elevation; Figure 4 is a sectional detail showing the ball and socket joint; Figure 5 is an elevation showing the opposite end of the structure from that delineated in Figure 3; 25 Figure 6 is a sectional view showing the coupling.

The numeral 3 designates suitable means for discharging water into a toilet 2 on the floor 1 of a car. Hangers 4 depend from the 30 floor 1 and carry a tank 5 supported from the floor by a brace 6, a pipe 18 leading from the toilet 2 to the tank. The tank 5 has a sloping bottom 7 provided in its lowermost portion with a depressed channel 8 communicating with a nipple 10 on one end wall of the tank. An angular spout 9 is provided. Any suitable means may be supplied for connecting the spout to the tank for swinging movement. If desired, the 35 spout 9 may have a flange 12 cooperating with a flange 11 on the nipple 10 of the tank, to receive a packing 50, a ring 14 being threaded on the flange 11 and having a lip 15 engaging the flange 12, a set screw 40 16 in the ring engaging the flange 11. Any suitable coupling, however, may be provided at the point indicated. The free end of the spout 9 is beveled as at 52 to fit against a wear plate 17 on the floor 1, when the spout 45 is swung upwardly.

The means for swinging the spout 9 embodies bearings 19 on the hangers 4, a shaft 20 being journaled in the bearings and being provided at one end with a crank arm 50 21 wherein a wrist pin 22 is rotatable. The

numeral 23 marks a crank arm having an angularly disposed finger 24 journaled and held in the wrist pin 22. The rod 23 is threaded for adjustment into a socket 25 terminating in a stem 28 connected by a ball 60 and socket joint 26 with a horizontally swinging arm 27 on the lower end of a shaft 29 journaled in a bearing 30 on the floor 1, the shaft terminating, above the floor, in a tubular head 31 adapted to receive a key 33 65 having a projection 34 received in a slot 32 in the head. A stop 35 on the floor 1 limits the swinging movement of the arm 27.

On that end of the shaft 20 which is remote from the arm 21 is fixed an arm 36. 70 There is an arm 37 on the spout 9. The ends of an angular link 38 are pivoted to the arms 36 and 37. A stop 39 on the adjacent end of the tank 5 limits the upward swinging movement of the arm 37. 75

When the spout 9 is swung upwardly into the position shown in Figure 5, the contents of the tank 5 cannot flow away, and the tank may be used freely, without depositing excreta on the ground. When the 80 car passes out of the city or other restricted area, an attendant seats the key 33 in the head 31 of the shaft 29 and rotates the shaft, the arm 27 and the connection 23 rotating the shaft 20 through the instrumentality of 85 the arm 21, the arm 36, the link 38 and the arm 37, swinging the spout 9 downwardly into the inclined position shown in dash line in Figure 5, whereupon the contents of the tank 5 will be discharged through the spout. 90

What is claimed is:

1. In a device of the class described, a tank; a toilet discharging thereinto; an angular spout constituting an outlet for the tank and rotatable thereon; and means under the control of an operator for swinging the spout upwardly and downwardly from a remote point. 95

2. In a device of the class described, a tank; a toilet discharging into the tank; 100 means for controlling the flow from the tank, said means embodying a shaft; and a key adapted for detachable connection with the shaft.

3. In a device of the class described, a 105 tank; a toilet discharging into the tank; an angular spout connected to the tank for swinging movement, and constituting an outlet for the tank; a shaft supported for rotation; means for connecting the shaft with 110

the spout; and means for operating the shaft from a remote point.

4. In a device of the class described, a floor; a tank located below the floor; a toilet disposed above the floor and discharging into the tank; an angular spout constituting an outlet for the tank and connected thereto for swinging movement; an arm on the spout; a shaft supported for rotation and having arms; a link connecting one arm of the shaft with the arm on the spout; a sec-

ond shaft rotatable in the floor and having an arm; and a connection between the arm on the second shaft and the other arm on the first specified shaft.

In testimony that I claim the foregoing as my own, I have hereto affixed my signature in the presence of two witnesses.

CHARLES C. MOORE.
